ABSTRACT: An electrical contact device comprising a housing having elongated recesses associated in pairs, extending at an acute angle and forming a channel. Spring loaded clamping members are arranged in the elongated recesses. Electrical conductors introduced through the elongated recesses are automatically locked and retained by the clamping members and the clamping members are tilted from their inoperative position into a position in which they rest against the electrical conductor.

ELECTRICAL CONTACT DEVICE

This is a continuation-in-part of my copending application Ser. No. 700,933 of Jan. 26, 1968, now U.S. Pat. No. 3,551,883.

It is already known to provide contact devices, e.g. terminals for connecting lighting installations, with self-locking clamping devices. Here the bared end of the wire is merely inserted and then slightly withdrawn, causing self-locking and a good contact. These devices have the advantage of eliminating screws or soldered joints. Generally the self-locking of the conductor end is achieved by a clamping member with an auxiliary spring. The known constructions have the disadvantage that the introduced conductor ends, particularly in the case of stranded wires, may easily foul the spring and block the same so that the self-locking effect does not occur. Larger contacting devices, intended for larger numbers of conductors or for the selective insertion of wires to make different connections are expensive and have therefore not been widely adopted. Another drawback of the known construction is that the self locking can be released only by means of special tools or not at all. Furthermore, with the increasing reduction in size, the manufacture of the known contact devices becomes increasingly more expensive, and with very small constructions handling and functional reliability of the known devices are increasingly insecure.

It is therefore an object of the present invention of providing a contact device of the kind hereinbefore described, whereby safe contact and easy release are combined with cheap manufacture and full functional reliability is ensured even with very small elements produced by mass production methods.

In the contacting device according to the invention the chamber is formed by two bores intersected at an acute angle, 35 wherein the spring retaining the clamping member is located in one bore and the electrical conductor in the other.

The invention will be further described by way of example with reference to the accompanying drawings, and in the appended claims.

In the drawings:

FIG. 1 is a view of a block-shaped contact device;

FIG. 2 is a perspective view of a disk-shaped contact device;

FIG. 3 shows the embodiment of FIG. 1 with the housing partly removed;

FIG. 4 is a cross section through the contact device of FIG. 3 along the line LI-LI;

FIG. 5 is a cross section of FIG. 4 with the housing fitted;

FIG. 6 is a partly broken away view in perspective of another embodiment of a terminal block;

FIG. 7 is a cross section of the FIG. 6 embodiment;

FIG. 8 is a cross section of an embodiment with an actuator common to several clamping bodies;

FIG. 9 is a cross section through the embodiment of FIG. 8;

FIG. 10 is another cross section through the embodiment of FIG. 8;

FIG. 11 shows a spring with clamping bodies;

FIG. 12 is a cross section of a plug combination;

FIG. 13 is a view of a guide member with hooked in spring end;

FIG. 14 is a front elevation of a clamping body;

FIG. 15 is a series terminal block with compressed air actuation;

FIG. 16 is a cross section along the line LXII-LXII in FIG. 15;

FIG. 17 is a perspective view in cross section, showing a contact strip;

FIG. 18 is a cross section of another construction of a terminal block;

FIG. 19 is a cross section of a single-pin plug embodiment;

FIG. 20 is a terminal block;

FIG. 21 is a cross section through the embodiment of FIG. 19;

FIG. 22 is a partial axial cross section of the embodiment of FIG. 20;

FIG. 23 is a cross section of another modification;
 FIG. 24 is a cross section of the embodiment of FIG. 23;
 FIG. 25 is an exploded view of the elements of FIG. 21;
 FIG. 26 is a side elevation of a clamping body;
 FIG. 27 is a further embodiment of a clamping body;
 FIG. 28 is yet another embodiment of a clamping body;
 FIG. 29 is an arrangement of clamping bodies with associated springs and slides;
 FIG. 30 is a modification of the embodiment of FIG. 29;
 FIG. 31 is a cross section of another embodiment;
 FIG. 32 is a cross section of an embodiment in which the conductor ends are fitted vertically from the top;
 FIG. 33 is a cross section of an embodiment in which the conductor ends are introduced horizontally;
 FIG. 34 shows a further terminal block in partial cross section;
 FIG. 35 shows a clamping body with clamping roller;
 FIG. 36 shows a pushbutton construction;
 FIG. 37 is a view in perspective of a dual switch;
 FIG. 38 is a plan view of the switch of FIG. 37;
 FIG. 39 is a cross section of the switch of FIG. 37;
 FIG. 40 is an axial cross section of a construction in which the clamping body is mounted on a leaf spring;

FIG. 41 is a top view of the embodiment of FIG. 40.
 The embodiment shown in FIGS. 1 to 4 consists of a block 301 with bores 5 either as blind bores or as continuous bores from one surface to another. Each bore 5 houses a spring 213 carrying a clamping member 8 at one or both ends. The clamping member 8 has a head 9 with a diameter slightly smaller than the inner diameter of the associated bore 5. As may be seen from FIG. 11 at least four steps 11 are connected to the head 9, the diameter of the last step being about two thirds of the diameter of the head 9. The last step 11 is connected to a neck 12, the end of which carries a ball 13, the diameter of which is about half that of the head 9 of the body 8. The length of the neck 12 between the last step and the ball 13 is substantially equal to the diameter of the ball 13. The clamping member may be of metal or plastic.

The spring 13 is preferably wound with increasing diameter so that the winding diameter is smaller at the ends than the diameter of the ball 13 at the end of the neck 12. In addition, the spring has a varying pitch so that the end turns have a substantially tighter spacing than the larger diameter turns more remote from the clamping member. In this manner the ball 13 of the clamping body 8 can be simply pushed into the end turns of the spring 213 for assembly. No special device is required for deforming the spring after the fitting of the clamping body, which remains connected thereto and cannot be detached, irrespective of the oblique positioning of the clamping member. The inner bores 5 extend in this embodiment parallel to an outer surface of the block 301, i.e. the axes are perpendicular to the front and rear sides 311 and 312 of the block 301. Further bores 7 extend obliquely to the bores 5 and end near the front side 311 or the rear side 312 of the block into the bores 5, forming with these chambers receiving the clamping bodies 8. The oblique bores 7 have a smaller diameter than the bores 5. One bore 5 and one bore 7 form an associated pair. Four pairs are arranged in the block, although the number of pairs of bores may obviously be varied at choice.

Where an insulation is not required for any reason, e.g. in telecommunication engineering, the end opening of the chamber common to the bores 5 and 7 is flanged over after the insertion of at least one spring 213 with clamping body 8, so that the body 8 can no longer be pushed out of the end face opening by the tension of the spring.

This crimping is not necessary if the front and rear faces are covered by plastic plates 314 which may be connected by a plastic frame 315 to a plastic housing completely surrounding the metal block 301. The plastic plates 314 contain then bores 316 which are aligned with the bores 7 and have preferably also the same diameter. When the bared end of a conductor is introduced into one of the bores 316 it passes automatically into the bore 7 whilst the clamping member 8 is pushed back.

If the conductor is withdrawn from the bore the clamping member 8 assumes an oblique position, and the spring follows this movement without detaching itself from the clamping member. The steps 11 all rest on the bare conductor end and lock the same automatically in position. The resulting good contact is highly insensitive to vibration.

Obviously the configuration of the block 301 can be adapted to widely varying applications. The edge length may amount for example to less than 1 cm. and more than 1 m. The block may also form part of an electrical apparatus. Strip-shaped arrangements with several hundred contacts are used for example for telephone switch gear, or for electronic computers. FIG. 2 is a disk-shaped embodiment of a plastic block 301a in which a larger number of bores 5 is arranged in a circle. The oblique bores 7 terminate at the surface of the disk-shaped body. This embodiment is suitable for example for the ignition circuit breaker in motor car engines.

In the embodiments shown in FIGS. 1 to 5, all conductor ends introduced into the block are electrically connected if the block 301 is of metal, e.g. of copper or brass. However, the block 301 may also be made of plastic; in this case conducting zones, e.g. in the form of powdered admixtures, metal plates, or sheet metal strips may be embedded in the plastic, except into the zone of the oblique bores 7 and being drilled during the drilling. Also, several conducting zones, such as strips may be arranged at narrow spacing adjacent to one another, wherein the inserted end of the conductor makes connection with several other bores. However, so long as no conductor end has been inserted into the associated bore the other bores are not connected or are connected by other paths. The bores may also be so manufactured that a framework of sleeves which are electrically conducting either wholly or in certain zones and which are correspondingly wired together, are cast into a plastic block. In the embodiment shown in FIG. 5, the block 301 may be made wholly of insulating material. In this case the conductor ends inserted into the bores 316 in the front face are each connected through the two clamping members 8 and springs 213 with the associated conductor end inserted on the rear side.

FIGS. 6 and 7 show an embodiment in which metal plates 318 are arranged parallel to each other and isolated by plates 319 of insulating material. As shown in FIG. 7 this arrangement is housed in a plastic housing 321 covered by a cover 322. For facilitating the assembly and improving the same, a bore 323 may extend between the bore 5 and perpendicularly thereto and a stud or screw may be fitted into this bore extending over the whole unit. In this embodiment the conductor ends fitted into the bore of a plate 318, for example a current lead and three current caps, are electrically connected, but the conductor ends are insulated against those fitted into the adjacent plate. The plates 319 of insulating material, separating the metal plates, serve also as abutments for the conductor ends introduced into the oblique bores 7. Thus when a certain length is observed for bearing the wire a good contact is always produced, i.e. the clamping member 8 does not make contact with an insulated part of the wire, and no bare wire is in front of the cover 322. In this way a large amount of safety may be produced for operation at higher voltages.

In the embodiments just described, the self-locking action may be released by introducing a pointed tool next to the conductor end and pushing the clamping body 8 back. If the conductors are to be released and possibly regrouped more frequently, an embodiment should be used whereby all conductor ends can be released simultaneously.

In the embodiment in FIG. 8 and 9 several metal sleeves 324 are arranged in a plastic housing 325 and held in spaced-apart relationship by spacers 326. The metal sleeves are slotted parallel to the inner bores 5 with the slots extending only over a part of the whole length. A pin 327 with an operating handle 221 outside the housing 325 is displaceable in the slots. Substantially in the center of the springs 213 a bored ball 329 is pushed between two turns of the springs and the pin 327 passes through the bores of the balls 329. If the actuating han-

dles 221 are pushed to the left, as viewed in the drawing, the clamping members 8 are pulled back from the associated guide faces on the inner wall of the plastic housing 325 and the self-locking effect acting on the conductors is released. If the operating handles 221 are pushed to the right, the left-hand clamping members 8 are withdrawn.

FIG. 13 shows a double-spring arrangement in which the ball 329 is replaced by a cylindrical guide member 329a having on both sides channel-shaped recesses 329b with disk-shaped ends 329c. The ends 329c have a slightly larger diameter than the end windings of the springs 213. The guide member 329a ensures the linear displacement in the inner bores 5 even where only one actuating handle 221 has been provided. This prevents tilting and jamming of the pin 327. Since the spring ends are simply pushed into the recesses 329b the assembly is very simple.

FIG. 14 shows that the clamping body 8 has at its head 9 a plate-shaped serration 306a. In embodiments without actuating means, a pin is engaged into the serration 306a for pushing back the clamping member 8. The serration 306a may be replaced also by any roughened portion.

In the embodiments of FIG. 15 to 19 the locking action is released by using a pressure medium, namely a gaseous medium under pressure or vacuum such as compressed air. In special cases also liquid media can be used particularly where other properties are utilized, e.g. where the same serves to improve the contacts or the insulation.

In the embodiments shown in FIG. 15 and 16, a plastic strip 35, containing fracturing points 36, comprises sleeves 1 the ends 6 of which terminate in inlets for a pressure medium and are arranged in spaced-apart relationship on the long sides of the plastic strip 35. For introducing the bare wire ends 506 to be connected there are oblique bores 7 leading to the upper surface of the plastic strip 35. For better guiding the bared wire end each sleeve 1 is pressed in as at 507.

The inner bore 5 of the sleeve receives a spring 21 wound in the shape of a double cone. Clamping members 8 are so hooked into the ends of the spring 21 as to permit a tilting movement. Each inner bore 5 communicates with an associated bore 508 for the pressure medium arranged on the upper side of the plastic strip 35.

The pressed in portions 507 have the effect of forming a venturi nozzle. If compressed air is applied to one of the openings 505 the compressed airflow pushes the clamping member 8 back against the force of the spring 21 and leaves through the associated outlet 508. The venturi effect creates a suction in the oblique bore 7 which substantially facilitates the introduction of the bare wire end 506. When the supply of compressed air is shut off the spring 21 tilts the clamping body 8 against the inserted wire 506, causing it to be locked. If required the wire can be changed for example for making new connections by applying compressed air.

Obviously instead of a pressure medium being applied to the inlets 505 it is also possible to apply a vacuum to the outlets 508, or both these features may be combined.

For the assembly on building sites or the like small portable apparatus with compressed air bottles may be used. Since the making of the connection in the apparatus according to the invention is achieved very quickly, a small airblast is sufficient.

It is also of interest to note that this embodiment is also suitable for wires which are so thin that they cannot be gripped with the usual screw connectors and which must not be kinked such as for example in electronic computers.

Where very small clamping bodies 8 must be used for connecting very thin wires it might, as shown in FIG. 17, be convenient to associate a piston 509 with each clamping member. The connection between the clamping body 8 and the piston 509 must however be such that the clamping body 8 and the piston 509 must however be such that the clamping body 8 can tilt into engagement with the introduced wire end 506. If a vacuum or suction is applied to the outlet 508, for example by means of a nozzle 511, the piston is retracted against the action of its associated spring 21. Conveniently the cross section

of the piston is smaller than the bore 5 of the sleeve 1. Consequently air is drawn in through the oblique bore 7 and this may substantially facilitate the introduction of the wire end 506.

The embodiment shown in FIG. 18 is particularly suitable for connecting the wire ends of larger cable trees 504. The oblique bore 7 cross obliquely substantially in the center of the sleeve 1. The outlets 508 are provided at the side of the terminal block whilst the inlets 505 are on its upper side between the bores 7. The springs 21 are secured by pins 512.

In the embodiment of FIG. 19 the sleeve 1 is housed in a single pin plug 514 having at its rear end an inlet 505. The outlet 508 may be provided on the surface of the single pin plug 514. However the deairing may also be effected through the plug pin. The wire end 506 to be connected to the plug 514 is clamped into a pan-shaped contact lug 515. The clamping member 8, having in this case no steps between head and neck rests under the action of the associated spring 21 in the cavity of the contact lug 505 and locks the same automatically.

If desired a larger number of clamping devices may be actuated together by using a nozzle connection 513, which as shown in FIG. 15 covers a larger number of inlets 505.

The embodiments shown are cheaper to manufacture than conventional terminal blocks and have the additional advantage that the introduction of wires at difficult points of access is much facilitated. The clamping members 8 may be plastic components easy to manufacture by mass production methods. The undoing of connections by unauthorized persons is less likely to occur than in conventional screw connections. If no compressed air source is available, the self-locking action can be released by introducing a pointed tool or a thicker wire into the flow inlet 505. The front face of the clamping element 8 has a serration or roughened portion to prevent the tool from slipping off. Where this is to be prevented, e.g. for connections to counters or monitors, the flow inlet 505, i.e. the channel leading to the clamping body 8 can be kinked or curved.

The terminal block embodiment shown in FIGS. 20 to 29 consists of a housing 601 of insulating material, made in two parts, i.e. prior to the assembly of the clamping element the housing consists of a base and an upper part which are joined by gluing or welding after the assembly. The upper part of the housing 601 has in its roof-shaped sloping sidewall inlets 602 into which the ends of the conductors to be connected are inserted. Between the inlets 602 are recesses in which a slide 603 is slidably mounted. To prevent the slide 603 from being lost they have projections 604 guided in associated grooves, as shown in FIG. 22. The wires 605 introduced through the opening 602 into a chamber 5, are locked in position by clamping elements 8 affected by the action of a helical spring 21. The clamping elements 8 have necks 12 and ball shaped ends 13 which are hooked into the springs 21. A part of the lower wall of the chamber 5 consists of a strip 609 of conducting material, having near the inlet orifices 602 punched obliquely downwardly extending tongues to form an oblique bore for the conductor ends 605.

The clamping elements 8 have each a bore 606', extending transversely to the conductor end 605, with a rod 606 passing therethrough. As shown in FIG. 29 this rod has thicker and thinner sections 607 which provide an equidistant spacing for the clamping elements 8 which are in this manner threaded on the rods 606. Since this threading can be done by machines a simple and convenient method of manufacture is provided by the invention.

The slides 603 have each two T-shaped slots 608'. They are fitted to the rods 606 by slightly pushing the same together against the force of the springs 21. After releasing the springs 21 the slides are firmly mounted on the rods 505 with the horizontal extending parts of slots 608.

In the embodiment of FIG. 23 the contact strip 609 has an oblique guide face for the inserted conductor end 605. The clamping elements may in this case be flat members. The insertion orifices 602 may also be slot-shaped, enabling for ex-

ample two conductor ends 605 to be gripped by the same clamping elements 8, FIGS. 27 and 28 show different embodiments of clamping elements.

FIG. 30 shows that also the slides 603 may be threaded on to the rods 606, i.e. horizontal slots 608' are provided for receiving the rods 606. A clamping element 8 and a slide 603 are alternatively fitted to the rods 606. A condition for the function is that the housing 601 is in two parts so that the arrangement of rods 606, clamping elements 8, helical springs 21 and slides 603 is fitted as a unit to the lower part of the housing 601. Then the upper part is mounted on the lower part.

FIG. 31 shows an embodiment which may have a very flat construction. They are particularly suitable for installations to be mounted under the plaster. The strip 609 forms two oblique abutments for the wire ends 605 to be introduced. To ensure the reliable fixing of the wire ends 605 on the strip 609, the latter has a groove recess 609' extending in the direction of the wire end and adapted to receive the same. Consequently the contact surface between the wire 605 and the strip 609 is increased and the transfer resistance is reduced.

The embodiment of FIG. 32 comprises a substantially V-shaped strip 609a. This embodiment is intended for installations in which the wire ends must be inserted vertically from the top. The axes of the helical springs 21 form an upwardly widening angle with one another, and with the inserted wires 605.

The embodiment shown in FIG. 33 is suitable where two aligned wires 605 have to be inserted from different sides. Since this arrangement may be very flat it is suitable for switches, plugs and similar installations. The strip 609b is bent in the shape of a roof and the conductor ends 605 are guided by punched lugs 609c.

FIG. 34 shows in perspective a terminal strip with fracturing points 611. At these fracturing points 611 the slide 603 may be omitted. If necessary a screwdriver may be used for moving the rod 606 to release a fitted wire end.

FIG. 35 shows that the clamping element 8 can be replaced by a clamping wheel 612 which carries a serration and is mounted rotatably in a cylindrical guide. The guide slides in a chamber 5'.

FIG. 36 illustrates that push buttons 613 can be used instead of the slides 603; to ensure a reliable guide of the pushbutton, the latter has preferably two guide lugs 604.

FIGS. 37 to 39 illustrate the installation of the device into a switch, with the special advantage that the switch housing may be very flat. Hence these embodiments are suitable for fitting under the plaster of thin walls such as partitions or other auxiliary walls. The conducting strip 609 in each chamber 5 is connected to a contact actuated by the switch handle.

The bores in the clamping elements 8 must always be large enough to provide sufficient play for tilting into the oblique position. Conveniently the points of attack are so chosen that the helical spring 21 pushes the clamping element into the oblique position.

In the embodiments of FIGS. 40 and 41, the bared conductor 1002 is inserted into a bore 1004 extending parallel to the base plate 1003 of a switch housing or housing of another installation element. The base plate 1003 of nonconducting plastic has a contact strip 1005 of metal which supports the conductor 1002. A blind bore 1020 extending obliquely to the bore 1004 forms with the latter a chamber 1009 which receives a clamping element 1007. The latter is hooked with its spherical end 1007a into a rhomb-shaped of a leaf spring 1018. For releasing the conductor ring the leaf spring 1018 may be pulled back by means of a clip 1021. The switch housing has a recess 1019 which substantially facilitates the fabrication and assembly of the unit. When the conductor 1002 is released, the clamping element 1007 swivels into the recess 1019.

I claim:

1. Apparatus for the detachable and self-locking clamping of a plurality of electrical conductors, comprising a housing

having a plurality of first and a plurality of second elongated recesses, each first elongated recess being in communication with an associated second elongated recess and the longitudinal axes of which form an acute angle with each other, each first elongated recess having at least one pressure spring with at least one associated clamping body biassed by the pressure spring, each second elongated recess adapted to receive an end of an associated electrical conductor, a plurality of openings arranged in at least one wall of the housing in communication with at least one of the elongated recesses for the introduction of the ends of the electrical conductors into the housing, each clamping body being pressed by the associated pressure spring in the direction towards the associated opening in the wall of the housing and at least one actuating means accessible from the outside of the housing whereby to push the clamping bodies back against the action of their associated pressure springs.

2. The device of claim 1 wherein said actuating means is in the form of a pressure medium source whereby a flow of pressure medium is passed through said first elongated recesses pushing back the clamping body against the face of the pressure spring.

3. The device of claim 2 wherein the chamber receiving the clamping body and formed both by the first elongated recess and the second elongated recess communicates with an inlet for the pressure medium and an outlet for the pressure medium and is shaped to form a venturi nozzle restriction upstream of the said chamber.

4. A device as set forth in claim 2, including channels interconnecting said elongated recesses so that a plurality of clamping bodies may be actuated simultaneously.

5. A device as set forth in claim 1, wherein two adjacent sets of elongated recesses are arranged in a terminal bar element and opposite elongated recesses of the two sets are arranged so as to form an acute angle opening in the direction of the electrical conductor to be inserted, wherein the housing consists of an insulating plastic and conducting strips are provided which connect facing elongated recesses.

6. A device as set forth in claim 1, wherein the housing is made of metal and plates of insulating material are mounted on two opposite faces of the housing, wherein the plates have elongated recesses for introducing the conductor ends and the clamping bodies are pressed by their associated spring against the edge of the elongated recess.

7. Apparatus according to claim 1, in which at least some of said first elongated recesses are blind-holes.

8. Apparatus according to claim 1, in which at least some of said second elongated recesses are blind-holes.

9. Apparatus according to claim 1 in which at least some of said first elongated recesses are through holes.

10. Apparatus according to claim 1 in which at least some of said second elongated recesses are through holes.

11. Apparatus according to claim 9, in which at least some of said second elongated recesses are through holes.

12. Apparatus according to claim 7, in which at least some of said second elongated recesses are blind-holes.

13. Apparatus according to claim 1, in which each first and each associated second elongated recess is in communication with each other in the region of the clamping body and in particular in the region of the opening in the housing wall.

14. Apparatus according to claim 1, in which means is provided in the housing for electrical contact of the inserted end of the electrical conductor.

15. Apparatus according to claim 1, in which means is provided for a tiltable connection between the pressure spring and the clamping body.

16. Apparatus according to claim 15, in which the externally accessible actuating means for pushing back the clamping bodies is connected with the clamping bodies over the associated pressure spring.

17. Apparatus according to claim 1, in which each clamping body has an approximately tear-shaped form in which at least a part of the surface of the clamping body is roughened.

18. Apparatus according to claim 17, in which each clamping body is provided with a stem having a spherically thickened end.

19. Apparatus according to claim 18, in which each pressure spring is wound as a conical coil spring in which the spherically thickened end of the stem is suspended in the end turn of the coil spring.

20. Apparatus according to claim 18, including a guide piece connected with the pressure spring in which the spherically thickened end of the stem of the clamping body is tiltably supported.

21. Apparatus according to claim 1, in which each first elongated recess forms a through hole which terminates in two housing wall openings which lie opposite each other, and the pressure spring is a coil spring with the shape of a double cone and each of its two ends is tiltably connected with a separate clamping body, said clamping bodies each facing towards the corresponding housing wall opening, each through hole being connected with two second elongated recesses in the region of the clamping bodies.

22. Apparatus according to claim 14, in which the inner walls of at least one of the elongated recesses consist of electrically conductive material.

23. Apparatus according to claim 1, in which the first elongated recesses are arranged in a plane alongside each other and the actuating means which is accessible from the outside consists of a rod which forms approximately a right angle with the first elongated recess, its end extending outward from the housing, a longitudinal slot in the wall of the first elongated recess, said rod being displaceable in the longitudinal direction of said slot.

24. Apparatus according to claim 23, in which a handle is fastened to each said rod extending out of the housing.

25. Apparatus according to claim 36, including longitudinal slots in the housing which are aligned with the longitudinal slots of the elongated recesses.

26. Apparatus according to claim 23, in which the rod passes through all adjacent clamping bodies which have through holes.

27. Apparatus according to claim 23, in which the clamping bodies have through holes and are rotatably mounted on the rod, the rod being preferably of plastic, having enlarged portions for the spacing of the clamping bodies.

28. Apparatus according to claim 23, in which there is provided two rods, each of which passes through a row of adjacent bored clamping bodies, each row of adjacent clamping bodies being fastened to the opposing ends of a row of associated coil springs lying alongside of each other.

29. Apparatus according to claim 28, in which the two rods are connected with a pusher which is slidably arranged in recesses of the housing.

30. Apparatus according to claim 23, in which each pressure spring is connected at its two opposite ends with a separate clamping body and is connected approximately at its center with the rod.

31. Apparatus according to claim 30, in which the connection of the rod with the pressure springs is by means of a bored ball connected with the pressure spring.

32. Apparatus according to claim 1, in which the first elongated recesses are approximately V-shaped.

33. Apparatus according to claim 1, in which the clamping bodies are approximately wedge-shaped and are provided with a ribbed surface.

34. Apparatus according to claim 23, in which the clamping bodies consist of a grooved roller which is rotatably fastened to an associated guide piece which is connected with the rod.

35. Apparatus according to claim 1, in which the first and the second elongated recesses are arranged in a plurality of plate-shaped conductive bodies which are electrically separated from each other by plastic boards and are combined into a block by a common plastic frame, and given clamping places in the block are conductively connected with each other.

36. Apparatus according to claim 1, in which the housing is a cylindrically shaped block of electrically conductive material.

37. Apparatus according to claim 1, in which the ends of the electrical conductors have spoon-shaped lugs which are clamped fast in self-locking fashion by the clamping bodies.

38. Apparatus according to claim 1, in which the connection of the first elongated recess with the second elongated recess forms a chamber.

39. Apparatus according to claim 1, in which the first recesses debouch into the openings in the housing wall.

40. Apparatus according to claim 1, in which the elongated recesses which receive the pressure springs and the clamping bodies are through holes and the housing consists of a block of electrically conductive material, the through holes passing from one sidewall of the block to the opposite sidewall.

41. Apparatus according to claim 40, in which the block is a cylindrical shape and the through holes debouch into the two end surfaces of the cylinder, while the second elongated recesses which are formed as bore holes emerge from the cylindrical surface of the cylinder.

42. The apparatus of claim 1 in which the plurality of openings in said wall is in communication with the first elongated recesses.

43. The apparatus of claim 1 in which the plurality of openings in said wall is in communication with the second elongated recesses.

44. Apparatus according to claim 1, in which each clamping body has an approximately tear-shaped form in which at least a part of the surface of the clamping body is provided with grooving.

45. Apparatus according to claim 1, in which the clamping bodies are approximately wedge-shaped and are provided with a roughened surface.

46. Apparatus according to claim 23, in which the clamping bodies consist of a grooved roller which is rotatably fastened to an associated guide piece which is connected with an associated pressure spring.

47. Apparatus according to claim 1 in which the second elongated recesses debouch into openings in the housing wall.
